[57] CLAIM

The ornamental design for a cap, as shown and described.

DESCRIPTION

FIG. 1 is a perspective elevational view of a cap embodying our new design;

FIG. 2 is a top view thereof;

FIG. 3 is an elevational side view thereof;

FIG. 4 is an elevational view of a first alternative embodiment thereof; and,

FIG. 5 is an elevational side view of a second alternative embodiment thereof.

The broken lines shown in the figures are for illustrative purposes only, and form no part of the claimed invention.
